DESIGN FOR A SERVICE STATION BUILDING OR THE LIKE

Charles A. Urbanek, Chicago, Ill., assignor to
Standard Oil Company, Chicago, Ill., a corpo-
ration of Indiana

Application March 24, 1934, Serial No. 51,169

Term of patent 7 years

To all whom it may concern:

Be it known that I, CHARLES A. URBANEK, a citizen of the United States, residing at Chicago, in the county of Cook and State of Illinois, have invented a new, original, and ornamental Design for a Service Station Building or the like, of which the following is a specification, reference being had to the accompanying drawing, forming part thereof, and in which

Figure 1 is a perspective view of a service station building according to my new design;

Figure 2 is a horizontal section, taken at window level, and showing the outline of the exterior walls of the service station building shown in Figure 1.

I claim:

The ornamental design for a service station building or the like, substantially as shown.

In witness whereof, I have affixed my signature.

CHARLES A. URBANEK.
